UNITED STATES PATENT OFFICE.

JOHN DENNISON McNEILL, OF CHICAGO, ILLINOIS.

METAL MOLD AND PROCESS OF MAKING THE SAME.

1,333,502.

Specification of Letters Patent.

Patented Mar. 9, 1920.

Application filed January 21, 1919. Serial No. 272,306.

To all whom it may concern:

Be it known that I, JOHN D. McNEILL, a citizen of the United States, residing at Chicago, county of Cook, and State of Illinois, have invented certain new and useful Improvements in Metal Molds and Processes of Making the Same, of which the following is a specification.

My invention relates to improvements in metal molds and process of making the same, and it consists in the combinations, constructions and arrangements herein described and claimed, and the steps herein-after described.

15 An object of my invention is to provide a metal mold from which a large number of castings can be made, thereby obviating the necessity of making a separate mold for each casting, as is done in the case of sand molds.

20 A further object of my invention is to provide a metal mold whereby the work of casting certain articles may be materially lessened and expedited, thereby tending to greater economy.

25 A further object of my invention is to provide a process for making the metal mold in a novel manner.

Other objects and advantages will appear 30 in the following specification, and the novel features of the invention will be particularly pointed out in the appended claims.

35 My invention is illustrated in the accompanying drawings, forming part of this application, in which—

Figure 1 is a longitudinal sectional view through a drag used in the process;

Fig. 2 is a perspective view of a metal half pattern;

40 Fig. 3 is a longitudinal sectional view of a half flask with a metal half pattern therein;

Fig. 4 is a perspective view of a half pattern with the projecting gate removed;

45 Fig. 5 is a sectional view through a half flask showing the manner in which the metal cope is formed; and

Fig. 6 is a sectional view through the completed metal mold.

50 In carrying out the process, I first place a drag (lower half flask) on a molding board with a half pattern such as a wood pattern, in position. Parting sand is then sifted over the pattern, this being followed 55 by the addition of facing sand, and then molding sand, all of which is rammed in and

around the pattern filling the flask. The top is leveled off, a molding board is placed on top, and the flask turned, or rolled over. The bottom board is now removed and the 60 cope (upper half flask) is placed on the drag, being held in position by flask pins at the sides. The upper half of the pattern is now placed in position, being alined with the half pattern just molded. Parting, fac- 65 ing and molding sand is sieved over it, and it is rammed, leveled, and afterward the flask is broken, the cope being lifted from the drag. The half patterns are then drawn and the gates are cut to permit the passage 70 of metal to the mold. The operation thus far described is ordinary, it being understood that this mold just referred to is the sand mold for the making of a metal pattern, and not the iron mold which is the 75 subject of this invention. The sand mold in the drag is shown in Fig. 1. In this figure the drag is shown at A, resting on the molding board B with the clamps C in position, the mold being shown at D. A metal plate 80 E is now placed over the top of the flask A with sand or metal cores F attached to the underside and projecting downwardly into the mold. A pouring hole G, and vent holes H, have previously been bored in the 85 plate E. The underside of the plate E may be coated with a graphite preparation before being placed in position to prevent amalgamation of the molten metal with the plate when poured.

90 The clamps C being in position and tightened to securely fasten the plate E to the drag, metal is now poured into the mold through the hole G, the generated gases escaping through the vents H. After being 95 poured, the metal is allowed to harden, and then the plate E is removed and the casting is removed from the sand. I now have a half metal pattern, such as that shown in Fig. 2 at K'.

100 The other portion of the metal half pattern is made in a similar manner in the cope. The projecting gate corresponding to the gate k in Fig. 2, is removed and a half pattern of metal is obtained, like that shown at 105 K² in Fig. 4. I now tap and thread holes J in the metal half patterns K' and K², and with the use of screws S, I securely fasten the metal pattern K' to the plate E. The plate E with the half pattern K' is now 110 placed in a half flask in which a layer of sand T has been placed in the bottom and

rammed. A similar sand protection T' is also provided for the sides of the half flask. As will be seen from Fig. 3, the plate E is in position with the pattern K' projecting 5 downwardly into the flask. Metal is now poured through the hole G around the pattern, the gases escaping through the vents H . After pouring, the plate E with the pattern K' attached is lifted off, and the 10 metal M forming the mold is sand blasted while still red hot in order to provide for a permanent facing protection. A metal drag has now been obtained as shown at M in Fig. 6.

15 The metal half pattern K^2 is secured to a plate E which is provided with pouring and vent holes as described in connection with the half pattern K' . An empty half flask A^2 is placed on a mold board B and 20 protecting sand layers T and T' are provided. Sand or metal cores O having anchoring pins P are placed in position on the layer T , the tops of these cores engaging the lower surface of the pattern K^2 . 25 Sprue hole core Q is secured in position by means of pins P at the top and bottom in the manner shown in Fig. 5, the bottom of the core resting on the layer T and the top of the core engaging the plate E . The 30 clamps C are placed in position and tightened. Molten metal is then poured through the hole G around the pattern K^2 and the cores O and Q , the gases escaping through the vent holes H . The plate E is then re- 35 moved and the surface of the mold is sand blasted when red hot, as previously described. The cores O and Q are broken and taken out.

I now insert sand cores W and a hollow 40 pouring core X in the metal cope R thus formed. The parts of the mold are now coated with graphite and may be placed together thus forming the complete mold U , as shown in Fig. 6.

45 In casting, metal is poured through the pouring hole X passing through the gate α into the interior of the mold. As the metal is poured, I prefer to exhaust the air from the mold by creating a partial vacuum in 50 the mold through the vent holes W , thus facilitating and hastening the escape of gases from the mold, accelerating the flow of metal into the mold, and thus preventing the accumulation of the gas in pockets 55 which, as is well known, greatly weakens a metal casting.

After pouring, the metal cope is lifted from the metal drag and the casting removed. The cope may be again placed in position and metal again poured in the mold 60 proceeding in like manner until any number of castings, exactly similar to the master pattern, are obtained.

It will be noted that the provision of the hollow sand cores for the pouring hole and the vents permits the breaking of the iron mold, *i.e.*, the separation of the parts of the mold. The cores may be readily replaced when necessary.

I claim:

1. A metal mold comprising a lower portion, an upper separable portion having a pouring opening, and vents, and frangible hollow cores for said pouring opening and said vents.

2. A metal mold comprising a lower portion having a gate, an upper separable portion having a pouring opening communicating with said gate and being provided with vents, and frangible hollow sand cores 80 disposed in said pouring opening and said vents.

3. The herein described process of making a metal mold which consists in suspending a half pattern in a half flask, and pouring metal into the space around said half pattern whereby half the mold is formed, suspending a second half pattern in a half flask, placing cores between said half pattern and the bottom of the flask, and a core 85 extending from the bottom to the top of the flask, and pouring in metal around said second half pattern and said cores whereby the other half of the mold is formed.

4. The herein described process of making 95 a metal mold which consists in suspending a half pattern in a half flask having a refractory lining, and pouring in metal around said half pattern whereby half the mold is formed, suspending a second half pattern 100 in a half flask, placing cores between said half pattern and the bottom of the flask, and a core extending from the bottom to the top of the flask, and pouring in metal around said second half pattern and said 105 cores whereby the other half of the mold is formed.

JOHN DENNISON McNEILL.
